(57) **CLAIM**

The ornamental design for a work light, as shown and described.

DESCRIPTION

FIG. 1 is a front, right and bottom perspective view of a work light showing my new design;

FIG. 2 is a rear, left and bottom perspective view thereof;

FIG. 3 is a rear, right and top perspective view thereof;

FIG. 4 is a front elevation view thereof;

FIG. 5 is a rear elevation view thereof;

FIG. 6 is a left side elevation view thereof;

FIG. 7 is a right side elevation view thereof;

FIG. 8 is a top plan view thereof; and,

FIG. 9 is a bottom plan view thereof.

The broken lines in the drawings depict portions of the work light that form no part of the claimed design.
